(57) **CLAIM**

The ornamental design for a lighting fixture, as shown and described.

DESCRIPTION

FIG. 1 is a front right perspective view from above of a lighting fixture according to the new design;
FIG. 2 is a front left perspective view from below thereof;
FIG. 3 is a rear left perspective view from below thereof;
FIG. 4 is a front elevational view thereof;
FIG. 5 is a right side elevational view thereof;
FIG. 6 is a left side elevational view thereof;
FIG. 7 is a rear elevational view thereof;
FIG. 8 is a top view thereof;
FIG. 9 is a bottom view thereof;
FIG. 10 is a front right perspective view from above thereof, but shown illuminated;
FIG. 11 is a front left perspective view from below thereof;
FIG. 12 is a rear left perspective view from below thereof;
FIG. 13 is a front elevational view thereof;
FIG. 14 is a right side elevational view thereof;
FIG. 15 is a left side elevational view thereof;
FIG. 16 is a rear elevational view thereof;
FIG. 17 is a top view thereof; and,
FIG. 18 is a bottom view thereof.

The broken lines shown in the drawings illustrate portions of the lighting fixture and form no part of the claimed design. The lighting fixture is shown with a symbolic break in its length and width. The appearance of any portion of the article between the break lines forms no part of the claimed design.

The stippling shown in FIGS. 10, 11 and 13 illustrate a change in appearance and does not represent texture or surface ornamentation.
